EXTRUSION APPARATUS

Richard A. Walton, Edwardsville, Ill., assignor to The Dow Chemical Company, Midland, Mich., a corporation of Delaware

Application March 9, 1956, Serial No. 570,586

1 Claim. (Cl. 207—2)

This invention relates to improved extrusion press apparatus and is particularly related to apparatus used in extruding wide, thin sections of light metal alloys.

Many wide, thin sections of light metal alloys are produced by an extrusion process. Because of the shape of the die used to produce the sections, dimensional problems due to uneven metal flow through the die have limited the applications in which such sections could be commercially used.

It has been determined that metal flows more uniformly through dies of the above described type if a container and ram having a rectangular transverse cross-sectional configuration is used. The use of rectangular containers results in greater adherence to dimensional tolerances than is generally obtainable with round bore containers and also result in lowered extrusion pressure. Further, when "rectangular" containers are used differences in properties between the nose and butt of an extrusion are greatly reduced and there is no necessity for providing complicated baffles for restricting metal flow to various parts of the die.

On the other hand, the use of rectangular containers is subject to some disadvantages. Rectangular containers require rectangular billets, and the scalping requires milling or planing rather than the inexpensive lathe turning used in scalping cylindrical billets. When rectangular containers are used, it is required to maintain wider variety of containers, rams and billets than are required in inventory when cylindrical containers are used in extrusion operations. Further, a rectangular ram is less stable in operation than is a cylindrical ram.

A principal object of this invention is to provide improved extrusion apparatus which has the operative advantages of a rectangular container without the inherent disadvantages attendant to the use of a rectangular container.

Another object of this invention is to provide improved, more economical apparatus for use in extruding wide, thin sections of light metals.

In accordance with this invention blocks are provided which are attached to the entry side of an extrusion die which is adapted for use with a cylindrical container. The blocks usually have a transverse cross sectional configuration which is a segment of a circle, the radius of curvature of each segment being that of the container. The blocks extend into the container and are usually disposed diametrically opposite one another with the die opening being between the blocks. Such an arrangement results in the die end of the container being effectively converted into a rectangular type container with the attendant advantages of such a container yet permitting a conventional round billet, container, and ram to be used in the extrusion operation.

The invention, as well as additional objects and advantages thereof, will best be understood when the following detailed description is read in connection with the accompanying drawing, in which:

Fig. 1 is a side elevational view, in section, of ex-

2

trusion apparatus incorporating sub-container blocks in accordance with this invention, and

Fig. 2 is a sectional view taken along the line 2—2 of Fig. 1, with no billet being shown in the container.

Referring to the drawing, both to Figs. 1 and 2, there is shown extrusion apparatus, indicated generally by the numeral 10, comprising a die holder 12 having a die 14 integral therewith, backer 16, blocker 18, and a generally cylindrical container, indicated generally by the numeral 20, which has a generally cylindrical bore 22 which is flared at the die end 24 of the container to fit snugly against a tapered side of the die holder 12. A cylindrically shaped ram head 26, disposed within the bore 22, is used to extrude a billet 28 through the die 14 to produce a metal section 32.

Sub-container blocks 34, 36 which have opposed parallel faces 33, 35 and 37, 39, respectively, are disposed within the container bore 22 and are secured by any convenient means, as by pins 38, to and against the entry side 40 of the die 14. Each of the blocks 34, 36 has a transverse cross sectional configuration which is a segment of a circle, the radius of curvature of the curved part of the outer periphery 42 of the blocks 34, 36 being substantially the same as the radius of curvature of the bore 22.

Each of the blocks 34, 36 is provided with a sloping entrance face 44, 46 which extends across that peripheral part of the blocks which is not shaped to conform to the curvature of the bore 22. Although the sloping entrance faces 44, 46 are very helpful in the operation of the blocks, they are not essential to the billet flow pattern into the die opening. The thickness or depth of the sub-container blocks (except for the sloping entrance faces 44, 46) as a minimum should be $\frac{3}{4}$ of the distance from the die opening to the block edge facing the die opening in order to insure uniformity of flow through the die 14. In practice, too, a minimum thickness of the sub-container blocks should be about $\frac{3}{4}$ inch and a maximum thickness should usually not exceed $1\frac{1}{2}$ inches because further increases in thickness tend to be no more beneficial. The spacing between the blocks 34, 36 does not exceed sixty degrees as measured radially from the center of the container bore 22 along the wall of the container bore 22 as may be seen in Fig. 2. The advantages of a rectangular container are mostly the result of container shape adjacent to the die opening rather than the shape of the containers at distances remote from the die opening.

In operation, a billet 28 is placed in the container bore 22 and is extruded through the die 14. The opening of the die 14 which is illustrated is used to produce flooring beams. The sub-container blocks 34, 36 cause the billet 28 to be broken up into a mass which has generally rectangular cross sectional configuration before the billet material passes through the die 14. The blocks 34, 36 cause more even metal flow through the die 14, resulting in less bending and distortion of the extruded section 32.

The blocks 34, 36 are so simple and inexpensive to make that a special set may be made for each die and permanently bolted thereto. Further, the use of sub-container blocks substantially reduces and often eliminates the need for separate baffle plates which often must be placed on the billet side of the die 14 to control the rate of flow of billet material to certain parts of the die.

In event billet material tends to slip between the curved outer periphery 42 of the blocks 34, 36 and the wall of the bore 22, the sloping entrance faces 44, 46 are so disposed that the pressure exerted on the faces 44, 46 by the billet material during extrusion operations keeps the blocks 34, 36 held against the wall of the bore 22.

The term "billet material" as used herein means light

metals or their alloys, extrudable plastic materials, or other metals adapted to be cold-extruded through die openings. Magnesium alloys are common alloys which may be extruded in apparatus in which sub-container blocks 34, 36 are incorporated.

That which is claimed is:

In extrusion apparatus which includes an extrusion press having an extrusion die including a die opening, said die communicating with and having a flat surface facing into a cylindrically shaped container bore having a generally cylindrical ram moveably disposed therein, the improvement comprising a pair of blocks disposed within said bore, each of said blocks having two parallel opposed surfaces, one of said parallel opposed surfaces of each block abutting against said flat die surface, each block having a peripheral surface which is disposed against said cylindrical bore in close fitting relationship therewith, each of said blocks having a plurality of means for maintaining said blocks in predetermined position within the bore and against said die surface, the blocks being disposed opposite to one another and on opposite sides of the die opening, the spacing between the

blocks being less than sixty degrees of arc as measured radially from the center of the bore along the bore wall between the blocks, whereby the general shape of the container adjacent to the die is changed from a cylindrical to a substantially rectangular cavity which conforms generally to the outline configuration of the die opening.
